[57] CLAIM

The ornamental design for paint brush having a manually operated handle pump connected by tubing to a paint container, as shown and described.

DESCRIPTION

FIG. 1 is a perspective view of a paint brush having a manually operated handle pump connected by tubing to a paint container showing my new design;

FIG. 2 is a top plan view thereof;

FIG. 3 is a bottom plan view thereof, and

FIG. 4 is a side elevational view thereof, shown with the tubing partially eliminated for ease of illustration.

FIG 2

FIG 3
